Patented Sept. 3, 1963

196,206

FOOT PUMP

Robert R. Mandy, Detroit, Mich., assignor to The Delman Company, Cookeville, Tenn., a corporation of Tennessee

Filed Dec. 31, 1962, Ser. No. 73,001

Term of patent 14 years

(Cl. D65—1)

FIG. 1 is a top plan view of a foot pump showing my new design;

FIG. 2 is a side elevational view of the same;

FIG. 3 is a bottom plan view of the same;

FIG. 4 is a back elevational view of the same; and

FIG. 5 is a front elevational view of the same.

I claim:

The ornamental design for a foot pump, substantially as shown.
